UNITED STATES PATENT OFFICE.

OSWALD S. PULLIAM, OF PITTSBURGH, PENNSYLVANIA, ASSIGNOR TO PITTSBURGH STEEL FOUNDRY COMPANY, OF PITTSBURGH, PENNSYLVANIA, A CORPORATION OF PENNSYLVANIA.

SIDE-FRAME CONSTRUCTION.

1,048,874.

Specification of Letters Patent. Patented Dec. 31, 1912.

Application filed April 5, 1911. Serial No. 619,042.

To all whom it may concern:

Be it known that I, OSWALD S. PULLIAM, of Pittsburgh, in the county of Allegheny and State of Pennsylvania, have invented 5 certain new and useful Improvements in Side-Frame Construction, of which the following is a specification.

An object of my invention is to provide a new and improved car truck side frame construction having separable journal-boxes, with the side frame proper and the journal-boxes having coacting means for securing the journal-boxes to the side frame.

A further object of the present invention 15 is to provide a new and improved side frame construction comprising a side frame proper having in addition to the means coacting with means on a separable journal-box for locking the same together, auxiliary means 20 coöperating with means for securing a standard journal-box of the usual and well known construction to the side frame.

A still further object of the present invention is to provide a side frame, and particularly a side frame of the type shown, 25 that will be considerably stronger at the juncture of the top-member and the oblique or inclined member, joining the top and bottom members, than has heretofore been the 30 case in integral cast metal side frames.

In the accompanying drawing, which illustrates applications of my invention, Figure 1 is a side elevational view of a side frame construction embodying my invention 35 showing a journal-box connected with the side frame proper at one end and a journal-box spaced away from the side frame at the opposite end; Fig. 2, a detail top plan of an end of the side frame; Fig. 3, a bottom 40 plan of the same; Fig. 4, a part elevational and a part sectional view taken on line IV-IV of Fig. 1; Fig. 5, a side elevational view of the journal-box of the form of Fig. 1; Fig. 6, a plan of said box; Fig. 7, a vertical 45 sectional view of the journal-box of the form of Fig. 5 particularly showing the lug on the top of the box and the manner of connecting same with an end of the side frame; Fig. 8, a detailed sectional view showing the 50 side frame proper in connection with a well known type of journal-box, and means for securing the journal-box to the side frame, the section of the side frame being taken on

line VIII-VIII of Fig. 2; Fig. 9, a side elevational view of a part of a side frame 55 and a detached journal-box showing a modified form of means for securing the box to the side frame; Fig. 10, a horizontal sectional view taken on line X-X of Fig. 9; and Fig. 11, an enlarged detail sectional view taken on line XI-XI of Fig. 1.

Referring to the drawing, the side frame comprises a top-member 1 terminating in end portions 2, said portions 2 comprising two spaced vertically extending members *a* 65 and *b* joined together by apertured lugs or cross pieces 3. Each of the members *a* and *b* is provided with an opening 4 adapted to receive a bolt or cotter pin 5. The side frame also includes a bottom-member 6 and 70 inclined members 7 connecting the top and bottom members. The side frame, as illustrated, comprises an integral cast steel structure formed, in addition to the elements mentioned, with a bolster receiving opening 75 8, columns 9, and a spring seat 10.

Attention is called to the construction of my side frame at the junctures of the upper end portions 2 and the inclined members 7, as illustrated, the vertically extending members *a* and *b* enter into the formation of the upper ends of the inclined members as particularly shown by Fig. 11, thus provided at points which have heretofore been weak, a 85 strong construction.

As shown in the form of Fig. 1, the side frame proper at each end thereof below the end portions 2, is provided with a journal-box engaging member 11. These members 11 are respectively supported by ribs 12 projecting outwardly from the inclined portions 7, and located at the lower ends of ribs 12, I provide an apertured member 13. The separable journal-boxes 14, shown in the form of Fig. 1, each has formed integral 90 with a side thereof a pocket 15, said pocket 15 being formed by vertically extending members 16 and a cross member 17 joining the said vertical members. Each of the vertical members 16 is formed with a groove 95 18 as particularly shown by Fig. 6. Located on and formed integral with the top of the box is an apertured lug 19.

In the embodiment of my invention as shown by Figs. 9 and 10 the coacting securing means of the frame and journal-box 105

are reversed, that is to say, in this form instead of forming a pocket on the journal-box I form the side frame with a pocket 15^a and the journal-box 14^a with an engaging member 11^a adapted to be entered in the pocket 15^a of the side frame. In other respects the construction of the form of Fig. 9 is substantially the same as the form of Fig. 1.

10. When the journal-boxes are applied to the side frame, the lug 19 of each box is placed between the vertical members *a* and *b* of an end portion 2 and the journal-box engaging member 11 entered in pocket 15 of the journal-box. The bolt or cotter pin 5 is passed through the openings in members *a* and *b* and through the apertured lug 19 as particularly shown by Fig. 7.

Fig. 8 shows a standard journal-box of well known construction applied to the side frame, in this instance I utilize the apertured members 3 of the end portions 2 for receiving box-bolts 21, which latter are passed down through the said members 3 and through lugs 22 formed on the journal-box 20. 23 designates a short tie-bar formed with openings 24 through which the bolts 21 pass and with a bent and apertured portion 25, adapted to engage the apertured member 13 of the side frame. The tie-bar 23 is secured at its inner end to the said member 13 by means of a bolt 26.

What I claim is:

1. A side frame comprising a top-member, a bottom-member, and an inclined-member connecting the top and bottom members, said top and inclined members at their juncture each having two spaced walls with the walls of the top-member merging into the walls of the inclined-member.

2. A side frame comprising a top-member, a bottom-member, and an inclined-member connecting the top and bottom members, said bottom and inclined members at their junctures being provided with two spaced merging walls.

3. The combination with a side frame comprising a top-member, a bottom-member, an inclined-member, and an upper end portion having two spaced vertically extending members entering into the formation of the upper end of the inclined-member, of a separable journal-box having a member entered between the spaced members, and means for securing the journal-box to the side frame.

4. The combination with a side frame comprising a top-member, a bottom-member, an inclined-member connecting the top and bottom members, said top and inclined members at their juncture each having two spaced walls with the walls of the top-member merging into the walls of the inclined-member, an upper end portion having two spaced members, and a separable journal-box having a member entered between the

spaced members of the end portion, and means for securing the journal-box to the end portion.

5. The combination with a side frame comprising a top-member, a bottom-member, an inclined member connecting the top and bottom members, said top and inclined members at their juncture each having two spaced walls with the walls of the top-member merging into the walls of the inclined-member, an upper end portion having two spaced members, a separable journal-box having a member entered between the spaced members of the end portion, and means on the inclined-member and the journal-box adapted to co-act in securing the journal-box to the side frame.

6. A side frame comprising a top-member, a bottom-member, an inclined-member having journal-box engaging means, and an upper end portion comprising vertically extending spaced members each provided with a bolt receiving opening.

7. A side frame comprising a top-member, a bottom-member, an inclined-member having journal-box engaging means and its upper end forked, and an upper end portion comprising two vertically extending spaced members and an apertured member connecting the spaced members, said spaced members entering into the formation of the forked portion of the inclined-member.

8. A side frame comprising a top-member, a bottom-member, an inclined-member having a forked upper end, and an upper end portion comprising two vertically extending spaced members and an apertured member connecting the spaced members.

9. The combination with a side frame having an end portion comprising two spaced members, a journal-box engaging member, a separable journal-box having a pocket formed on a side thereof and an apertured lug on its top, said apertured lug entered between the vertical members of the end portion and the engaging member in the pocket of the journal-box.

10. The combination with a side frame having a top-member, a bottom-member, an inclined-member joining the top and bottom members, an upper end portion comprising two vertically extending spaced members, a separable journal-box having an apertured lug on its top, said apertured lug entered between the vertical members of the end portion, and means for securing the lug to the spaced members.

11. The combination with a side frame comprising a top-member having an end portion comprising spaced vertically extending members, a member connecting the spaced members, an inclined-member, a member projecting downwardly from the inclined-member, a separable journal-box, a tie-bar secured to the downwardly project-

ing member, and a bolt connecting the tie-bar and the member joining the spaced members of the end portion.

12. The combination with a side frame including a top-member, a bottom-member, an inclined-member joining the top and bottom members having an outwardly projecting member, said top-member formed with a projecting end portion, a separable journal-
10 box, a tie-bar secured to the projection of

the inclined-member, and means connecting the tie-bar and the projecting end of the top-member.

In testimony whereof I affix my signature in presence of two witnesses.

OSWALD S. PULLIAM.
